UNITED STATES PATENT OFFICE.

NICHOLAS RAPPLEYEA AND WILLIAM A. SPARKS, OF HOBOKEN, NEW JERSEY,
ASSIGNORS TO NATIONAL CASKET COMPANY, OF SAME PLACE.

DESIGN FOR A CASKET-LID.

SPECIFICATION forming part of Design No. 35,011, dated August 27, 1901.

Application filed August 2, 1901. Serial No. 70,674. Term of patent 14 years.

To all whom it may concern:

Be it known that we, NICHOLAS RAPPLEYEA and WILLIAM A. SPARKS, of Hoboken, in the county of Hudson and State of New Jersey, have invented and produced a new and original Design for Casket-Lids, of which the following is a description.

The drawing is a perspective view of a casket-lid embodying our design. The leading feature of our design consists of a casket-lid formed with end panels A and an intermediate panel C for the name-plate, said intermediate panel having its upper face c inclined from a point in proximity to one end panel toward the other end panel. The sides c' of the intermediate panel converge upwardly from their lower portions toward the upper face c.

A casket-lid embodying our design presents a pleasing and characteristic appearance. 20

Having described our invention, what we claim as new, and desire to secure by Letters Patent, is—

The design for a casket-lid, substantially as herein shown and described. 25

In testimony whereof we have hereunto signed our names, in the presence of two attesting witnesses, at Hoboken, in the county of Hudson, in the State of New Jersey, this 24th day of July, 1901.

NICHOLAS RAPPLEYEA.
WILLIAM A. SPARKS.

Witnesses:

JOHN L. HOAGLAND,
JOHN P. KENNEDY.
